SPLITTING SHEET MATERIAL

Charles E. Johnson, Belmont, Mass., assignor to
United Shoe Machinery Corporation, Borough
of Flemington, N. J., a corporation of New
Jersey

Application December 17, 1938, Serial No. 246,391

7 Claims. (Cl. 12—17)

This invention relates to machines for operating upon pieces of work and is herein illustrated as embodied in a machine for splitting a sole-shaped blank into an outsole having a projection on its forepart and an insole having a correspondingly located complementary opening.

In the splitting of such blanks it is common to make use of a machine having a knife and a pair of matrix and patrinx-rolls which act to feed the blank past the knife and to distort a portion which is split in such manner as to cause the cut of the knife to form the projection and the complementary opening referred to above. A comparatively heavy pressure must be applied to the blank to distort it but a less pressure is desirable during the splitting of that portion of the blank which is not distorted.

According to the present invention there is provided a machine for operating upon a piece of work and means for applying a greater pressure to one portion of the piece than to another during the said operation. In the illustrated machine a sole-shaped blank is split by means of a knife to which the blank is fed by cooperating matrix and patrinx rolls which distort a portion of the blank during part of the splitting operation and maintain another portion undistorted, two means being provided for causing relative movement of approach of the rolls, both means being effective during the splitting of the distorted portion of the blank and only one means being effective during the splitting of an undistorted portion.

These and other features of the invention, including certain details of construction and combination of parts of the machine, will be set forth as embodied in an illustrated machine and pointed out in the appended claims.

Referring to the accompanying drawing:

40 Fig. 1 is a vertical section of a portion of a machine in which the present invention is embodied; and

Fig. 2 is a vertical longitudinal section through a portion of a piece of work after it has been operated upon by the machine.

The illustrated machine is an improvement upon the machine of United States Letters Patent No. 2,082,057, granted June 1, 1937, upon an application filed in the name of Charles E. Hood; and before describing what is new a brief description of the old machine will be given. The purpose of the machine is to split a sole-shaped blank into an outsole having a projection on its forepart and an insole having a correspondingly located complementary opening which may, or

may not, extend entirely through said insole. The machine is provided with a matrix roll 5 and a patrinx roll 7, which are rotated intermittently in the directions indicated by the arrows, and with a stationary knife 9. The rolls come to rest spaced apart a distance which is just slightly less than the thickness of a sole-shaped blank 100, which is to be split. A single rotation of the rolls is started by depressing the treadle, not shown, and this depression of the treadle also starts the downward presentation of a blank 100, which engages with its forward end a toe gage 11 on the patrinx roll 7. This is the position of the parts shown. During the completion of the rotation of the rolls, the blank is split into an 15 outsole 200 having a projection 300 on its forepart and an insole 400 having a correspondingly located complementary opening. The sole blank herein illustrated consists of a comparatively thin layer 500 of a material such, for example, 20 as paper impregnated with latex and a comparatively thick layer 600 of leather, the insole 400, which is split off, being a laminated one. This sort of a blank has been chosen for illustration for reasons which will appear later. 25

The illustrated machine differs from the patented machine in the feature, immaterial so far as the present invention is concerned, that the matrix and patrinx rolls have been transposed so that in the illustrated machine the patrinx roll 30 is the roll which yields; and the brief description of the patented machine, which follows, should be read with this change in mind. The illustrated machine, like that of the machine of the patent, is double, that is, there are two patrices 35 on the patrinx roll and two matrices on the matrix roll so that blanks are split two at a time by the knife, but since the patrices and matrices are alike only one patrinx and its cooperating matrix will be referred to. The matrix roll 5 is rotatably mounted in a roll-carrier comprising a pair of arms connected by a web, one of which arms is shown at 13, said arms being pivoted at their upper ends about the alined axes of trunnions, not shown. The roll carrier consisting of the 40 connected arms 13 may be adjusted manually about the axes of the trunnions about which the arms are pivoted so as to vary the distance from the edge of the knife to the adjacent surface of the roll. After this roll-carrier has been so 45 adjusted the matrix roll is not bodily movable during the splitting of the blank. The patrinx roll 7 is rotatably mounted in a second roll-carrier comprising a pair of arms, one of which is shown at 15, said arms, like the arms 13, being 50

pivoted at their upper ends about the axes of trunnions, not shown. Two coiled springs, one of which is shown at 17, acting respectively upon the arms 15 of this second roll-carrier tend at all 5 times to swing it to the left and thus to move the patrix roll bodily toward the matrix roll. The angular position of the roll-carrier comprising the arms 15, and hence the distance of the patrix roll from the matrix roll, when no 10 work is passing through the machine, is determined by the position of a rod 19 which is mounted in bores in the lower ends of the arms 15. This rod 19 is moved bodily at times to the right into the position shown and is afterward 15 permitted to be moved to the left by the springs 17. The bodily movement of the rod 19 to the right is caused by movement of a slide rod 21, which is mounted in the frame of the machine and is moved lengthwise at certain times to limit 20 the extent of possible movement of the patrix roll toward the matrix roll. Certain opposed beveled portions on the rods 19 and 21 are not 25 shown but there is shown one of the slideable pins 23, the opposite beveled ends of which engage the beveled portions of the rods, so that sliding of the rod 21 swings the patrix roll-carrier to the right against the force of the springs 17.

In the operation of the machine the rod 21 30 is automatically moved in and out at the proper times to control the extent to which the patrix roll can be moved to the left. The machine comes to rest after one revolution of the rolls with the patrix roll held away from the matrix roll, so 35 that the space between them is sufficient to permit the leading end of the blank to enter readily between the rolls. When the forward end of the blank so enters and is contacted by the patrix, the patrix roll is moved somewhat to the right 40 against the force of the springs 17, these springs exerting a heavy pressure since the forepart of the blank must be distorted while it is being split. It is desirable, when the blank is 45 presented to the rolls, that the rolls should be held spaced somewhat as described above so as to ensure that in the rotation of the rolls the patrix cannot contact with the knife but they should not be so held during the entire splitting operation. Instead, the springs 17 should be 50 permitted to move the patrix roll nearer to the matrix roll during the latter portion of the splitting operation so as to ensure that the blank will be discharged from the machine. To this 55 end the rod 21 which, before the machine came to rest, was slid in a direction to prevent the patrix roll from being moved nearer to the matrix roll than the position shown in the drawing, is slid in the other direction to free the patrix roll after the splitting of the distorted portion of the sole has been completed. This release of the 60 patrix roll takes place after distortion of the forepart of the blank and the cutting of the projection 300 on the outsole has been completed and during the splitting of the shank portion of the 65 blank. The machine, as thus far described, is, or may be, the same as the machine of the patent with the immaterial difference referred to above, that the matrix and patrix rolls have been transposed, and with the further difference 70 that the springs 17 of the illustrated machine exert less pressure than the corresponding springs of the patented machine, the reason for this latter difference being explained below.

When the splitting of the distorted forepart 75 of the blank has been completed and the patrix

roll is released, a suddenly applied heavy pressure is exerted upon the blank over a comparatively small area, this sudden pressure having the approximate effect of a blow which sometimes causes the cut of the knife to change its 5 direction, this objectionable result being particularly likely to occur when the blank is a laminated one. Referring to Fig. 2 at about the locality indicated by the arrow, the patrix roll, which is in contact with the layer 500, is released 10 and suddenly exerts a heavy pressure at this locality. When this occurs, the cut 700 may be deflected toward the layer 500 and, if it is sufficiently deflected to reach the joint 800 between the layer 500 and the leather, it tends to follow 15 this joint during the completion of the splitting operation. A heavy pressure is necessary during the splitting of the distorted portion of the blank but a lesser pressure is sufficient during the splitting of that portion of the blank which is not 20 distorted.

According to the present invention, a heavy pressure is applied when it is needed, namely, during the distortion of the blank, and a less pressure while the blank is not being distorted. 25 To this end the springs 17 are made lighter than those of the patented machine, or the screw bolts, one of which is shown at 23 which vary the tension of these springs, are backed off; and the patrix roll is urged toward the matrix roll during 30 the distortion of the blank not only by these springs 17 but by other means which do not act upon the patrix roll when that roll is released to press upon that portion of the blank which is not distorted. As herein illustrated, two spring-pressed plungers, one of which is shown at 25, are provided to act respectively upon the lower ends of the two arms 15 of the patrix-roll-carrier. These plungers and the manner in which they are mounted are alike. The stem of each plunger 35 40 is slideable in a bore in the cylindrical reduced end of a casing 26, said reduced end being threaded into a bore in a portion of the frame 27 of the machine and held in place by a lock nut 29. The enlarged end of this casing has a 45 bore to receive a compression spring 31, the tension of which may be varied by turning a screw-bolt 33 threaded through a cap 35 which is fastened to the outer open end of the casing 26 by screw-bolts 37. The spring 31 is located 50 between the head of the plunger 25 and a disk 39, against which one end of the screw-bolt 33 bears. By turning the casings 26, the normal position of the plungers may be varied and by turning the screw-bolts 33, the tension of the 55 springs 31 may be varied; and since the plungers 25 act upon the lower ends of the arms of the roll-carrier, they are more effective by reason of the leverage thus attained than are the springs 17.

It has been explained that the plungers 25 60 are spring-pressed. It should be noted, however, that the springs 31 which act upon the plungers can be compressed, if desired, by turning the screw-bolts 33 until the springs will no longer yield, in which case the plungers 25 are rigidly held. In such case the normal positions of the plungers are so adjusted with reference to the thickness of the blanks to be split that just sufficient pressure will be exerted to distort the blanks 65 70 during the action of the patrix.

When the machine comes to rest with the patrix roll held spaced as shown from the matrix roll, the ends of the plungers 25 are just touching the lower ends of the arms 15 of the patrix-roll- 75

carrier. As soon as the forward end of a blank 100 has entered between the rolls, the plungers 25 become effective and act in conjunction with the spring 17 to distort the forepart of the blank 5 while the matrix and the patrix rolls are in contact with it. When, after the completion of the splitting of that portion of the blank which is distorted, the patrix roll is released by the action of the slide rod 21 so that said roll moves nearer 10 to the matrix roll, the plungers 25 are no longer effective, and the patrix roll is pressed against the blank only by the springs 17. Thus a heavier pressure is applied to the blank while it is being distorted and a lighter pressure while it is not 15 being distorted. No heavy blow or its equivalent is imparted to the blank, for example at the locality indicated by the arrow in Fig. 2, and no deflection of the cut of the knife ensues.

Although the invention has been set forth as 20 embodied in a particular machine, it should be understood that the invention is not limited in the scope of its application to the particular machine which has been shown and described.

Having described my invention, what I claim 25 as new and desire to secure by Letters Patent of the United States is:

1. A splitting machine having in combination a knife, a patrix roll and a cooperating matrix roll 30 for feeding past the knife a blank which is wider at one portion than at another and for distorting the wider portion of the blank while it is being split, and two means for resisting relative movement of separation of the rolls, both means being effective during the splitting of a distorted portion 35 of the blank and only one of the two being effective during the splitting of an undistorted portion.

2. A splitting machine having in combination a knife, a patrix roll and a cooperating matrix roll for feeding past the knife a blank which is 40 wider at one portion than at another and for distorting the wider portion of the blank while it is being split, and two yielding means for resisting relative movement of separation of the rolls, both means being effective during the splitting of a distorted portion of the blank and only one of the two being effective during the splitting of an undistorted portion.

3. A machine for splitting a blank which is 45 wider at one portion than at another and for distorting the wider portion of the blank during the splitting operation, said machine comprising a roll and a presser for forcing a portion of the blank into the matrix, means for preventing the matrix roll and the presser from approaching nearer to each other than a given distance during the splitting of the distorted portion of the blank and for permitting nearer approach during

the splitting of an undistorted portion, and two means acting to resist relative separation of the matrix roll and the presser, both of said means being effective during the splitting of the wider distorted portion of the blank and only one being 5 effective during the splitting of the narrower undistorted portion.

4. A machine for splitting a blank of compressible material which is wider at one portion than at another, having in combination a knife 10 and a pair of rolls for feeding the blank past the knife, said rolls being shaped to bend the wider portion but not the narrower portion of the blank, and two means for resisting movement of separation of said rolls during the distortion of the wider portion of the blank, one of the means becoming 15 ineffective when the narrower unbent portion of the blank is being split.

5. A machine for splitting a blank of compressible material which is wider at one portion than at another, having in combination a knife 20 and a pair of rolls for feeding the blank past the knife, said rolls being shaped to bend the wider but not the narrower portion of the blank and one of said rolls being bodily movable toward and 25 from the other, means for resisting movement of separation of the rolls at all times, and other means acting in conjunction with said first-named means for increasing the force of the resistance during the bending of the wider portion, 30 said other means being inoperative during the splitting of the narrower portion of the blank.

6. A machine for splitting a blank of compressible material which is wider at one portion than at another, having in combination a knife 35 and a pair of rolls for feeding the blank past the knife, said rolls being shaped to bend the wider but not the narrower portion of the blank and one of said rolls being bodily movable toward and from the other, and yielding means for resisting 40 movement of separation of the rolls during the bending operation with a force of a given magnitude and for resisting such movement with a force of less magnitude during the splitting of the narrower portion, the decrease in magnitude being 45 greatly in excess of any change in tension due to expansion of the yielding means caused by movement of approach of the rolls.

7. A machine of the class described having in combination a knife, a matrix roll and a cooperating 50 presser for feeding the work to the knife and for distorting a portion of the work, a greater force being necessary to feed and distort the work than to feed it, means for exerting a yielding force at all times to resist separation of the 55 roll and presser, and means acting to increase the force during the distortion of the work.

CHARLES E. JOHNSON.
